RECONNAISSANCE INSTRUMENT

Eugene Lodwick Hartley, Jr., Batesburg, S. C.

Application October 9, 1942, Serial No. 461,495

8 Claims.

(Cl. 33—1)

This invention relates to reconnaissance instruments, and more particularly to an instrument using in mapping, to accurately graph elevations, contours and variations in the earth's surface.

With present day instruments, it is difficult to map wooded areas, particularly jungle country, due to the low visibility and underbrush. With present day instruments it is necessary to cut a considerable path in order that the surveyors may see each other.

An object of this invention is to provide a portable accurate measuring and recording device which may be used in any type of country and which will only require a sufficient clearing to allow a line to pass through.

A further object is to provide a device of the character described wherein the calculations are automatic, and the possibility of human error is reduced to a minimum.

It is also an object of the invention to provide a device of the character described in which not only are the calculations made automatically, but in which they are automatically recorded.

The purpose of this device is to record not only contours and other variations in the earth's surface, but also the direction in which these contours run and the path of travel of the surveying crew.

In my invention a line is drawn from the device against spring pressure from the starting point over the area to be surveyed. The machine is then set, as will hereinafter be explained, and the line returned. As the line is returned, stylographs record on graph paper the contours and direction of the ground covered.

In the accompanying drawings—

Fig. 1 is a plan view of the device embodying my invention;

Fig. 2 is a cross sectional view thereof taken on the line 2—2 of Fig. 1;

Fig. 3 is an end view of the device;

Fig. 4 is a cross sectional view taken on the line 4—4 of Fig. 1;

Fig. 5 is a cross sectional view taken on the line 5—5 of Fig. 1;

Fig. 6 is a cross sectional view taken on the line 6—6 of Fig. 1;

Fig. 7 is an end view from the opposite end of Fig. 3;

Fig. 8 is a cross sectional view taken on the line 8—8 of Fig. 1;

Fig. 9 is an enlarged detail view showing the

operation of the line, taken on the line 9—9 of Fig. 13;

Fig. 10 is a detail view showing the operation of the pressure wheels;

Fig. 11 is a detail view of a train of gears used to rotate one of the rollers;

Fig. 12 is a plan view of the rollers and stylographs used;

Fig. 13 is a cross sectional view taken on the line 13—13 of Fig. 2;

Figs. 14 and 15 are detail views in section of a stylograph mounting;

Fig. 16 is a detail view showing the operation of the directional control apparatus;

Fig. 17 is a detail view showing the operation of the contour control apparatus;

Fig. 18 is a diagrammatical view showing the manner in which the instrument is used.

Referring to Fig. 18, it will be noted that where rising ground is being plotted, the elevation causes the distance between two points to be increased. The figure also shows the manner in which the string or line is used to take measurements. It will be noted that the instrument is held a definite distance A above the ground. This requires that the line operator hold the end of the string the same distance above the ground and a stick or rule may be used for this purpose. While not specifically shown, straps or harness may be provided to position the instrument on the chest of the operator.

My device includes a casing 20 having a transparent top 21 hinged at 22 to the casing. Mounted in the casing are rolls 23 and 24 bearing graph paper, as is indicated in Fig. 12. The larger squares in the graph may represent any predetermined distance, and arrangement is made so that this distance may be varied by interchangeable gears, which will be described later. By way of example, one of the larger squares may represent 100 feet or 500 feet, depending upon the necessity for detailed information.

Mounted in the cover 21 is a compass scale 25 and a magnetic needle 26. Above the needle are cross scales 27 and 28 mounted at right angles to each other. Levels 29 and 30 are mounted at right angles to each other so that the operator may accurately level the entire device.

The scales 27 and 28 are mounted on threaded rods 31 and 32 which are connected by a train of gears and rods to the knobs 33 and 34 as is clearly shown in Fig. 16. Thus it will be seen that by turning the knobs 33 and 34, the operator can cause the scales 27 and 28 to move so that the

cross hairs on said scales may be made to coincide at a point immediately above the point of the compass needle. While not shown in Fig. 16, the rod 35, leading to the threaded rod 31, and the end of the threaded rod 32, are provided with universal joints 36 (Figs. 1 and 2) to allow the lid to be opened.

In addition to operating the threaded rod 31, the knob 33 is connected by a train of gears to the threaded rod 37, upon which is mounted by an internally threaded mount, the roller 38. Similarly, the knob 34 controls the turning of the threaded rod 39, upon which is mounted the roller 40. The rollers used throughout, and there are four of them, are substantially the same in detail. Fig. 10 shows one of these rollers which includes the wheel 41 having a gear 42 attached, which, in turn, contacts an idler 43, which idler engages the pinion rod 44.

It will be seen that by operating the knob 33 the operator not only causes the scale 27 to move, but at the same time changes the position of the roller 38 on the disc 45. Similarly, the movement of the knob 34 moves the scale 28 and changes the position of the roller 40 on the disc 46. The roller 38 is operatively connected to the pinion rod 47 and the roller 40 is operatively connected to the pinion rod 48. The rod 48 is operatively connected by means of a train of gears by the rod 49 to the threaded rod 50 on which is mounted the stylograph 51.

When the disc rotates, as will hereinafter be explained, the movement is transmitted through the roller 40, the rod 48, and through the threaded rod 50, to move the stylograph along the roll 24 to rotate the roll to a degree and direction depending upon the position of the roller 38. Obviously, the amount of movement of the stylograph and the roll will be dependent upon the position of the rollers 38 and 40 with relation to the center of the discs 45 and 46, there being no movement when the rollers are positioned at the center of the discs, and there being an increasing movement as the rollers are moved toward the periphery of the discs.

The movement of the roll 23 is controlled by a similar mechanism including the combination of discs and friction rollers, the positions of which are controlled by the knobs 60 and 61, which, likewise control the vertical scales 62 and 63. In order to secure the proper contact reading after the device is leveled, the position of the string with relation to the device is noted in the mirror 64 and the knobs 60 and 61 are manipulated until the cross hairs of the scales 62 and 63 coincide with the string, as shown in Fig. 3.

The scale 62 is mounted on the threaded rod 65 which is connected by a train of gears and rods to, and is rotated by, the knob 60, as clearly shown in Fig. 17. The scale 63 is mounted on the threaded rod 66 which, in turn, is controlled by the knob 61. The movement of the knob 60 likewise rotates the threaded rod 67 on which is mounted the roller 68. The movement of the knob 61 likewise controls the rotation of the threaded rod 69 on which is mounted the roller 70. The roller 68 contacts the disc 71 and is operatively engaged to the pinion rod 72. The roller 70 contacts the disc 73 and is operatively engaged to the pinion rod 74.

The rod 74 is connected by a train of gears and the rod 75 to the threaded shaft 76 on which is mounted the stylograph 77. The rod 72 is operatively connected by means of gears and the worm 78 to the geared end 79 of the roll 23. Thus

it will be seen that the position of the roller 65 on the disc 71 will control the movement of the roll 23 while the position of the roller 70 on the disc 73 will control the movement of the stylograph 77.

The worm 78 is mounted in a bracket 110 having elongated slots 112 to allow the position of the bracket to be shifted so that the gear 114 may be removed and a larger or smaller gear substituted to vary the movement of the roll so that it will coincide with the desired value of each square on the graph.

In the base of the device is a coiled spring 80 mounted on the shaft 81. The shaft 81 engages the gear 82 which meshes with the gear 83 which is geared to the hub 84 of the reel 85 on which is mounted a line of light cord or string. The string moves through a guide 86 over a pulley 87 and out through openings 88 in the side of the device. On the rear of the pulley is a ratchet 89 and a gear 90. The gear 90 is provided with a pawl 91 to engage the ratchet 89 when the rotation of the pulley is counter-clockwise. The pulley 89 and the gear 90 are mounted on a shaft in a slidable mount 92, as shown in Fig. 13. The mount 92 may be moved either way to accommodate different sizes of gears 90. This variation is provided in order to vary the value of the large squares on the graph paper, the larger the gear being used, the larger the value of the squares expressed in terms of distance.

The gear 90 meshes with a pinion 93 on a shaft 94 which has at its end a worm 95 engaging the gear 96 on the hub 97 supporting the discs 71 and 73. Pinion rod 74 engages a gear 99 which operates the pinions 100 and 101. Pinion 100 is mounted on a shaft 102 having a worm 103 engaging the worm gear 104 on the hub of the disc 46. Pinion 101 is mounted on a shaft 105 having a similar worm 106 engaging the worm gear 107 on the base of the disc 45.

In operation, in the field, the operator stands at the starting point, as indicated in Fig. 18. His assistant then takes the line or string and walks outwardly over the ground to be plotted. If the ground is rolling, then only a relatively short distance may be covered, say, from one depression to the top of the next rise. If the rise or fall is constant, a greater distance may be covered.

As the string is moved outwardly from the box, the pulley 87 will be turned, but the pawl 91 will slide over the ratchet 89 so that no motion will be transmitted to the mechanism. As soon as the predetermined point is reached, the assistant stops and holds the string the proper distance above the ground. The operator then levels the box and manipulates the knobs 33 and 34 until the cross hairs of the scales 27 and 28 coincide with the point of the compass needle 26. As has previously been explained, this will cause friction rollers 38 and 40 to assume the proper position on the discs 45 and 46.

Glancing into the mirror 64, the operator then manipulates the knobs 60 and 61 until the cross hairs of the scales 62 and 63 coincide with the line or string, as shown in Fig. 3. This causes rollers 68 and 69 to assume the proper position on the discs 71 and 73. It will be noted that each of the rollers, with the exception of the roller 40, is free to move completely across the face of the disc so as to reverse the direction of rotation of the roller. Since the roller 40 determines the forward motion of the stylograph

77, and since this motion is always forward, it is not necessary to reverse it. The stylographs are so constructed that they may be moved to the left hand of the machine without turning the threaded rods on which they are mounted. As is shown in Figs. 14 and 15, the stylograph is mounted on a base 115 which is provided with a spring clamp 116, the jaws of which are internally threaded. By compressing the handle members 117, the stylograph may be manually moved to the starting position. 10

Having adjusted the controls, as outlined above, the operator may either walk toward his assistant, or vice versa, or the string may be allowed to come back onto the reel 85, in any desired manner, it being understood that the action of the spring will cause the string to return. As the string returns over the pulley 87, turning the pulley in a counter-clockwise direction, pawl 91 will engage the ratchet 89 and transmit power through the shaft 94 to rotate all of the discs 45, 46, 71 and 73. The rotation of the discs will transmit power to the rollers 38, 40, 68 and 70. This movement will be transmitted to the several stylographs and rolls, it being understood that the movement transmitted through the rollers 40 and 70 will move the stylographs along their threaded rods 50 and 76, while the movement transmitted to the rollers 38 and 68 gives the rolls 23 and 24 rotary movement. The operation may then be repeated to continue the charting of the terrain.

It will be appreciated that it is not necessary for the crew to operate in a series of straight lines, and the second operation may be on an angle from the first. The variance will be recorded on the roll 23 as is indicated thereon. When the graph is removed from the rolls, it is only necessary for a map maker to know the starting point. He may then chart their direction and the contour of the ground, which is indicated on the roll 24.

While I have shown specific mechanism for the synchronous operation of the rollers and scales and the transmission of the motion of the returning string to the stylographs and rolls, it will be readily appreciated that various gear hook-ups may be used to accomplish this purpose without departing from the spirit of my invention. It will also be appreciated that the size of the instrument and manufacturing convenience may dictate changes in the specific arrangement and construction.

I claim:

1. A surveying instrument including a case, a reel of line in said case, spring means for normally retaining said line in a retracted position, a pulley contacting said line, a plurality of discs operatively connected for rotation to said pulley, friction rollers on said discs, means for varying the position of said friction rollers with relation to the center of said discs, recording rolls, stylographs operatively positioned on said recording rolls, means connecting said friction rollers with said stylographs and with said rolls, sliding scales, means for positioning said scales, said means being operatively connected to said roller positioning means, whereby the position of said scales determines the position of said rollers on said friction discs.

2. The combination with a recording roll having a stylograph operatively positioned with relation thereto, of separate means for rotating said roll and moving said stylograph, said means including a pair of discs mounted for rotation,

friction rollers engaging said discs, a pair of cross scales mounted at right angles to each other, a pair of knobs each operatively connected to one of said friction rollers and to one of said scales, whereby the operation of each of said knobs will cause the movement of one of said scales and change the position of one of said friction rollers with relation to the center of said disc. 5

3. A surveying instrument including a case, a reel in said case, a line on said reel; means for normally maintaining said line in a retracted position, leveling means on said case, a magnetic needle mounted on said case, cross scales adjustably mounted above said needle, vertical scales on the side of said case adjacent said line, means for varying the position of said scales to coincide with said compass needle and with said line, recording rolls, stylographs operatively positioned with relation to said rolls, and means cooperating with said line for recording the return movement of said line on said rolls by means of said stylographs, said means being controlled by said scale adjusting means.

4. A mapping instrument including a case, a pair of recording rolls mounted in said case, stylographs operatively positioned with relation to said recording rolls, a disc mounted for rotation for each of said stylographs and for each of said rolls, a friction roller on each of said discs adapted to transmit movement of said disc to one of said rolls or stylographs, two pairs of cross scales, one pair of said scales being adapted to cooperate with a magnetic needle to indicate direction, a reel of line adapted to be drawn out of said case 30 for measuring purposes and adapted to cooperate with the other pair of said scales to record direction and elevation, means for simultaneously moving each of said scales and its corresponding friction roller with relation to the center of the corresponding disc, and means cooperating with said line to rotate said discs when said line is returned to said case.

5. In a mapping instrument, a pair of recording rolls, stylographs operatively positioned with relation to each recording roll, one of said recording rolls being adapted to record direction, the other of said recording rolls being adapted to record distance and elevation, means for rotating 45 each of said rolls and for moving each of said stylographs with relation thereto, said means including discs or each stylograph and roll, a friction roller on each of said discs operatively connected to one of said stylographs or one of said rolls, a line in said instrument adapted to be stretched from said instrument to a predetermined point, means operated by the retraction of said line to rotate said discs, a pair of cross scales on said instrument, one of said pair of scales being adapted to control the recording of direction, the other of said pair of scales being adapted to record elevation, and control members for moving each of said scales to the desired position, and to simultaneously move one of said friction rollers on its disc with relation to the center thereof, whereby the direction and amount of rotation of each of said rolls and the direction and amount of movement of each of said stylographs upon the retraction of said line is automatically predetermined.

6. A mapping instrument operated by a line, spring means for normally maintaining said line in a retracted position, a pair of recording rolls, stylographs operatively positioned with relation to said rolls, one of said rolls being adapted to

record the direction of the extension of said line, the other of said rolls being adapted to record the elevation of said line upon extension, mechanism for rotating said rolls and moving said stylographs upon the retraction of said line, a magnetic needle, a pair of cross scales, means for setting one of said pair of cross scales to coincide with the point of said magnetic needle, additional means for setting the other of said pair of cross scales to coincide with said line when extended, and additional means connected to the scale setting means to adjust said mechanism, whereby the amount of movement of said rolls and stylographs upon the retraction of said line is automatically predetermined.

7. A surveying instrument including a case, means for leveling the case, a reel of line in said case, spring means in said case for normally retaining said line retracted, a pulley in said case engaged by said line, rotatable discs in said case, interchangeable gearing geared to said pulley and discs, friction rollers which cooperate with said discs respectively, means for varying the po-

sition of said friction rollers with relation to the center of said discs, recording rolls in said case, stylographs for the recording rolls respectively, means operatively connecting each of said friction rollers and its respective stylograph, means operatively connecting each of said friction rollers with said interchangeable gearing, said interchangeable gearing being operatively connected with said recording rolls to operate them in response to the return movement of said line, two pairs of sliding scales carried by said case, scale positioning means operatively connected with said friction rollers respectively whereby the position of said scales determines the position of said friction rollers on said discs, and one pair of scales when set coinciding with said line when extended.

8. A survey instrument as set forth in claim 7, and a magnetic compass carried by said case, and the second pair of scales when set coinciding with the point of the compass needle.

EUGENE LODWICK HARTLEY, JR.
